UNITED STATES PATENT OFFICE.

ALBERT M. PIGEON, OF PHILADELPHIA, PENNSYLVANIA, ASSIGNOR TO PIGEON MACHINE COMPANY, OF PHILADELPHIA, PENNSYLVANIA, A CORPORATION OF PENNSYLVANIA.

PICKER MECHANISM AND CONTROLLING-CAM FOR KNITTING-MACHINES.

1,247,324.

Specification of Letters Patent. Patented Nov. 20, 1917.

Application filed October 25, 1912. Serial No. 727,703.

To all whom it may concern:

Be it known that I, ALBERT M. PIGEON, of Philadelphia, in the county of Philadelphia and State of Pennsylvania, have invented certain new and useful Improvements in Picker Mechanism and Controlling-Cams for Knitting-Machines, whereof the following is a specification, reference being had to the accompanying drawings.

10 The invention relates more particularly to the pull-down picker mechanism and to the controlling cams which raise the long butt needles to inactive position for knitting the heel and toe pockets of a stocking, and

15 which lower said long butt needles to active position for circular knitting.

An object of the invention is to provide a down picker mechanism wherein independent pickers may be utilized for moving the 20 needles into active position for the widening of the toe and heel pockets of a stocking.

A further object of the invention is to provide means common to both pull-down pickers for simultaneously rendering the same 25 inactive when the parts of the knitting machine are adjusted for circular knitting.

A further object of the invention consists in providing separately mounted cams which 30 are independently and alternately operated for either raising the long butt needles to inactive position, or for depressing said long butt needles to active knitting position.

These and other objects will in part be 35 obvious, and will in part be hereinafter more fully described.

In the drawings which show by way of illustration one embodiment of the invention, Figure I, is a vertical sectional view 40 through a portion of a knitting machine having my improvements applied thereto.

Fig. II, is a side view of a portion of the upper end of said knitting machine.

Fig. III, is a plan view showing the controlling cams and the pull-down pickers.

Fig. IV, is a diagrammatic view, showing the relative position of the pull-down pickers, the controlling cams, the stitch cams, and the narrowing pickers.

50 Fig. V, is a detail view showing the pull down pickers when released so as to be in active position.

Fig. VI, is a sectional view on the line

VI, VI, of Fig. V, showing the springs for operating the pull down pickers.

55

In the present embodiment of the invention, the knitting machine consists generally in a needle cylinder which is formed with radial ribs providing channels for spring beard needles. These needles are raised 60 and lowered by the usual knitting cams. Said needles are formed in two series, one of which is provided with long butts and the other with short butts, so that the two series may be controlled, as is common in the 65 art for circular knitting, or for knitting the heel and toe pockets of a stocking.

Cooperating with the needles are pickers which are brought into operation during the knitting of the heel and toe pockets or narrowing and widening the same. The pickers for narrowing the heel and toe pockets are of the usual construction. The picker mechanism for widening the heel and toe

70

pockets comprises two independently mounted pickers, one of which is active when the cylinder is moved in one direction, and the other of which is active when the cylinder is moved in the opposite direction. These independent pickers are mounted on a bracket

75

and so supported as to move at an angle to the plane of travel of the cylinder. The two pickers are rendered inoperative during circular knitting by a rod which is common to both pickers, and which is moved into 80 contact therewith through a suitable mechanism controlled by the shifting of the clutch to bring about the change in the movement of the needle cylinder.

The long butt needles are moved to inactive 90 position by a raising cam, and are brought again to active position by a depressing cam.

This raising cam is mounted independently of the lowering cam and the two cams are alternately moved into operative position by 95 suitable mechanism, also controlled by the shifting of the clutch which changes the movement of the needle cylinder.

Referring more in detail to the drawings, the invention consists in a needle cylinder 100 1, which is provided with radial ribs 2, forming needle channels, in each of which is a spring beard needle 3. This spring beard needle is attached, as herein shown, to a needle jack 4, having a butt 5, adapted 105 to be engaged by suitable knitting cams,

While I have shown the needle as attached to a needle jack it will be obvious that the invention is not directed to this feature of the machine, and the needle butts may be formed directly on the needles. Hereinafter I shall refer to the needles as having long and short butts, and this will be understood as covering either the form wherein an independent jack is used, or where the needle butt is formed directly on the needle.

As clearly shown in Fig. I, the butt 5, of the needle jack on the right hand of the figure is longer than the butt 5, of the needle jack on the left of the figure. I have divided the needles into two series, which are substantially equal in number, and one of the series has the long butts and the other the short butts, as above noted.

The needle cylinder 1, is attached to a gear 6, at the lower end thereof, and said gear rests on a supporting bracket 7, which may be raised and lowered for raising and lowering the needle cylinder to fashion the stocking. The gear 6, meshes with a gear 8, which is mounted to rotate on the main frame 9, and said gear 8, is fixedly attached to a bevel gear 10. The bevel gear 10, is rotated for rotating the needle cylinder, or oscillated for causing the needle cylinder to oscillate. This rotating of the needle cylinder and the oscillating thereof, is controlled by the shifting of the clutch, which in turn is controlled by a suitable pattern mechanism, as is common in this type of machine, and further description or illustration thereof is not thought necessary.

The needles are supplied with the yarn from a suitable yarn guide, and the beards of the needles are depressed in proper timed relation to the rotation or oscillation of the cylinder, so that loops formed around the shanks of the needles may be shed therefrom. The manner of feeding the yarn to the needles, the supporting of the yarn, and the closing of the beards of the needles, form no part of the present invention, and a detailed description thereof is not thought necessary.

Referring to Fig. IV, I have shown diagrammatically the cams and pickers controlling the needles during the knitting of the circular web, and also the heel and toe pockets when the machine is operated for knitting stockings. In this view, the stitch cams are indicated at 11, and 12, and coöperating with each stitch cam is a switch cam 13, and 14, respectively. A picker 15, operates to raise the needles of the short butt series when forming the heel and toe pockets, one at a time to inactive position when the needle cylinder is moving in one direction, and the picker 16, operates to raise one needle at a time at the other end of the series to inactive position when the needle cylinder is moving in the opposite

direction. These stitch cams, switch cams and pickers, form no part of the present invention, and further description thereof is not thought necessary.

The needles of the short butt series are brought again to active position for widening the heel and toe pockets, by pickers 17, and 18. After the finishing of the heel pocket and also after finishing the toe pocket, it is desirable to bring the needles with the long butts into active position for the circular knitting. This is accomplished by the throwing down cam or lowering cam 20. At the beginning of the heel pocket, and at the beginning of the toe pocket, these long butt needles are moved to inactive position by a raising cam 21.

The pickers 17, and 18, are separately mounted. The picker 18, is formed with a picker head and a shank 22, which is mounted in a suitable socket in an arm 23, pivoted at 24, to a bracket 25, which in turn is pivoted by a screw 26, to a standard 27, fixedly attached to the supporting frame 9, of the machine. The bracket 25, is formed with a vertical face which rests against the standard, and this bracket is adapted to swing in a vertical plane. A stop screw 28, is carried by the swinging bracket, and is adapted to engage the standard to limit the swinging movement of the bracket on its supporting pivot 26. This stop screw is held in various adjusted positions by a lock nut 29.

The bracket 25, is formed with a lateral projection which has an upper inclined face 30. The arm 23, carrying the picker 18, rests on this inclined face, and is adapted to swing in a plane parallel with said inclined face. It will thus be apparent that the picker 18, may be swung in a vertical plane by the movement of the swinging bracket 25, and may be swung in a plane at an angle thereto by the movement of the supporting arm on the swinging bracket. These combined movements permit the picker to move in the proper direction for sliding the needles in their channels from inactive to active position. As a matter of fact, the picker is so formed that two needles are simultaneously engaged and move from inactive to active position.

The picker 19, is similarly mounted and constructed, and the parts for supporting the same have been similarly numbered, and the description for one will answer for the other, the only difference between the two pickers being that the supporting face of the swinging bracket for the picker 19, is inclined in the opposite direction to the supporting face on the bracket for the picker 18.

The arm 23, for supporting the picker, strikes against the supporting bracket which limits its movement in a direction

toward the supporting standard. Suitable springs 60, are provided for normally holding the pickers in active position.

The pickers are moved to inactive position for circular knitting by a rod 31. Each of the swinging brackets is formed with an upwardly projecting lug 32. This rod 31, is carried by a lever 33, see Fig. III. The lever 33, is pivoted at 34, to the frame of the machine. Said lever projects rearwardly to a point where it may be operated by some of the shifting parts which are moved when the clutch is shifted for bringing about a change in the movement of the needle cylinder. When the rod is moved toward the needle cylinder, the lugs 32, will be engaged, and the pickers swung about their pivotal supports to inactive position. When the rod is moved in the opposite direction, the pickers are released, and the springs will throw the pickers into active position.

The operation of the pickers will be apparent from Fig. IV. These pickers co-operate, as above noted, with the leading needles of the short butt needles, which are to be thrown down to active position. Each picker is formed with an inclined outer face 35, also with an overhanging lip 36, and a chamfered lower face 37. When the needles are moving in the direction of the arrow, Fig. IV, the butts which contact with the picker 17, will depress the same and ride over this picker, which will be ineffective to disturb the position of the needle butts. The advance needle butts of the series will engage underneath the overhanging lip 36, of the picker 18, and the movement of the cylinder will swing the picker in such direction as to carry the butts engaged thereby down to active position, so that said needle butts will be engaged by the stitch cams. When the needles are moving in the direction indicated, the stitch cam 12, becomes effective for bringing about the movement of the needles for knitting.

When the cylinder is moving in the opposite direction, the picker 18, becomes ineffective in a similar manner, and the advance needle butts will be brought into contact with the side face of the picker 17, underneath the projecting lip thereon, and said picker will operate to carry the two needle butts engaged thereby to active knitting position, and when the cylinder is moving in this direction, the stitch cam 11, becomes effective.

The lower ends of the pickers are chamfered, so as to permit said picker heads to slide over the tops of the needle butts or disengage the same when said needle butts have been moved to the full lower level.

In order to insure the needle butts being positioned at the proper level for engage-

ment with the pickers, I have provided a fixed guard cam 38, which is mounted on the standard 27, supporting the pickers. This cam 38, will engage the needle butts if they are accidentally moved to an improper height, and lower the same so as to bring them into proper engagement with the pickers.

From the above description, the operation of the pickers for moving the needles for widening the heel and toe pockets will be obvious. It will be noted that I have provided two independently movable pickers, one of which is active when the needle cylinder is moving in one direction, and the other of which is active when the needle cylinder is moving in the opposite direction. These pickers also may be simultaneously moved to inoperative position when the parts are positioned for circular knitting.

The raising cam 21, which engages the long butt needles for moving the same to idle position, is mounted on a lever 39, which is pivoted on a vertical stud 40, carried by the supporting frame of the machine. This lever 39, projects beyond the supporting stud, and is provided with a vertically extending pin 41. The lowering cam 20, is mounted on an arm 42, which is also fulcrumed about the stud 40, and movable independently of the lever 39, carried thereby.

A spring 43, is fixed to the lever 39, and engages the bracket on which the picker 15, is mounted, and operates to hold said raising cam 21, in position for engaging the long butt needles. A spring 44, is fixed to the arm 42, and co-operates with a fixed part on the frame, so as to normally press the cam 20, toward the needle cylinder. A bracket 45, is carried by a suitable arm 46, which is attached to the cross rod which is moved endwise when the clutch is shifted for changing from one movement to the other of the needle cylinder. This bracket 45, is provided with an arm 47, which is so positioned as to engage the pin 41, when the bracket is moved toward the needle cylinder.

The bracket is also provided with an arm 48, having a slot 49, therein, adapted to engage a pin 50, carried by the lever 42. When the bracket 45, is moved toward the needle cylinder, the pin 41, will be engaged, and the cam 21, withdrawn from the needle cylinder. This movement of the bracket also causes the arm 48, to release the pin 50, and allows the spring 44, to move the cam 20, toward the needle cylinder. When the bracket 45, is moved in the opposite direction, the end of the slot 49, engages the pin 50, and withdraws the cam 20. At the same time, the arm 47, moves out of contact with the pin 41, and allows the spring 43, to move the cam 21, toward the needle cylinder.

Mounted on the bracket 45, and movable

therewith, is an arm 51, which is adapted to engage a pin 52, carried by the picker 15. When the bracket 45, is moved toward the needle cylinder, this throws the cam 20, into 6 action, which positions the needles for circular knitting. This movement of the bracket will move the picker 15, out of operative position, so that it will not engage the needle butts during the rotations of the cylinder.

10 It will thus be seen that I have provided raising and lowering cams for the long butt needles which are separately mounted, and which are independently actuated for moving the same into and out of operative position relative to the needle cylinder.

15 It is obvious that minor changes in the details of construction and arrangement of parts may be made, without departing from the spirit of the invention, as set forth in the 20 appended claims.

Having thus described my invention, I claim:

1. In a knitting machine, the combination of a needle cylinder, a plurality of needles 25 having butts, or the like, carried by said cylinder, widening pickers, means for separately supporting said pickers, whereby said pickers may be moved independently of each other, the outer faces of said pickers being

30 oppositely tapered so that one picker becomes effective when the needle cylinder is moving in one direction, and the other picker becomes effective when the needle cylinder is moving in the opposite direction, each of 35 said picker heads having the lower face thereof chamfered for freeing the butts of the active series and for releasing the picker heads from the needle butts.

2. In a knitting machine, the combination 40 of a needle cylinder, a plurality of needles having butts, or the like, carried by the cylinder, a widening picker for actively engaging the needle butts when the cylinder is moved in one direction, and a widening

45 picker for actively engaging the needle butts when the cylinder is moved in the opposite direction, a supporting arm for each picker, a swinging bracket for each picker arm, a standard to which the swinging brackets are

50 pivoted, so as to swing in vertical planes, and substantially radially of the needle cylinder, said widening pickers being turnable about pivots on the brackets inclined to the vertical, and means for holding the pickers 55 in operative position relative to the needle cylinder.

3. In a knitting machine, the combination 60 of a needle cylinder, a plurality of needles having butts, or the like, carried by the cylinder, a widening picker for actively engaging the needle butts when the cylinder is moved in one direction, and a widening picker for actively engaging the needle butts when the cylinder is moved in the opposite 65 direction, a supporting arm for each picker,

a radially swinging bracket for each picker arm, a standard to which the swinging brackets are pivoted, so as to swing in vertical planes, means automatically swinging said brackets radially for holding the pickers in operative position relative to the needle cylinder, and means for simultaneously engaging the swinging brackets for moving said pickers to inoperative position.

4. In a knitting machine, the combination 75 of a needle cylinder, a plurality of needles having butts, or the like, carried by the cylinder, a widening picker for actively engaging the needle butts when the cylinder is moved in one direction, and a widening

80 picker for actively engaging the needle butts when the cylinder is moved in the opposite direction, a supporting arm for each picker, a radially swinging bracket for each picker arm, a standard to which the swinging 85 brackets are pivoted, so as to swing in vertical planes, means automatically swinging said brackets radially for holding the pickers in operative position relative to the needle cylinder, each of said swinging brackets 90 having a vertically extending lug, a rod for engaging said lug, and means for moving said rod to render said pickers inoperative.

5. In a knitting machine, the combination 95 of a needle cylinder, a series of needles having long butts, and a series of needles having short butts, a cam for raising the needles having long butts to idle position, a cam for lowering said needles to active position, means for separately supporting said cams, 100 springs for independently moving said cams toward the needle cylinder, a laterally shiftable bracket, and arms carried thereby and adapted to alternately engage said cams for moving the same away from the needle cylinder.

6. In a knitting machine, the combination 110 of a needle cylinder, a series of needles having long butts, and a series of needles having short butts, a cam for raising the needles having long butts to idle position, a cam for lowering said needles to active position, means for separately supporting said cams, 115 springs for independently moving said cams toward the needle cylinder, a laterally shiftable bracket, an arm carried thereby for engaging and moving one cam away from the cylinder when the bracket moves toward the cylinder, and a second arm carried by said bracket for engaging and moving the other 120 cam away from the cylinder when the bracket moves away from the cylinder.

7. In a knitting machine, the combination 125 of a needle cylinder, a series of needles having long butts, and a series of needles having short butts, a cam for raising the needles having long butts to idle position, a cam for lowering said needles to active position, means for separately supporting said cams, 130 springs for normally pressing the cams to-

ward the needle cylinder, a bracket, moved toward and from the needle cylinder when the clutch is shifted for changing the movement of the needle cylinder, arms carried by 5 said bracket coöperating with said supporting means for the cams, whereby said cams are alternately moved toward and from the needle cylinder by the shifting of the bracket, a narrowing picker, and an arm 10 carried by said bracket for engaging and

moving said narrowing picker to inoperative position, when said long butt needles are lowered to active position.

In testimony whereof, I have hereunto signed my name at Philadelphia, Pennsylvania, this twenty-first day of October, 1912. 15

ALBERT M. PIGEON.
